UNITED STATES PATENT OFFICE.

LOUIS JOSEPH EMMANUEL COLARDEAU AND JULES RICHARD, OF PARIS, FRANCE.

AUTOMATIC DEVICE FOR CONTROLLING THE OPERATION OF PHOTOGRAPHIC APPARATUS.

1,104,412.

Specification of Letters Patent.

Patented July 21, 1914.

Application filed February 10, 1913. Serial No. 747,513.

To all whom it may concern:

Be it known that we, LOUIS JOSEPH EMMANUEL COLARDEAU, of 13 Rue de Navarin, professor at the College Rollin, and JULES RICHARD, of 25 Rue Mélingue, scientific-instrument maker, both in the city of Paris, Republic of France, have invented an Improved Automatic Device for Controlling the Operation of Photographic Apparatus, of which the following is a full, clear, and exact description.

The present invention has for its object an automatic device applicable to photographic apparatus and permitting the operator to photograph himself or to appear in a group or landscape taken by himself.

This device permits a time-exposure as well as an instantaneous view to be taken; it has for its result to produce successively:

- 20 1. The appearance of a signal indicating that the shutter of the photographic apparatus is about to open; 2, the opening of the shutter; 3, the closure of the shutter after the desired time of exposure has elapsed; 25 4, which time is determined in advance; 4, the appearance of a second signal indicating that the photograph is taken.

The new device is characterized essentially by a mechanism which acts twice on the press-button or presser-piece of the shutter, the first time in order to open it, the second time in order to close it, this second action taking place after the desired time of exposure has elapsed; this mechanism determines moreover the appearance of the second signal, indicating that the taking of the photograph is completed.

The arrangement forming the object of the invention is represented in the accompanying drawings, which are given by way of example only, wherein:

Figure 1 shows in elevation the device mounted on a photographic camera. Fig. 2 is a corresponding side view. Fig. 3 is a plan view partly in section on the line A—A, Fig. 1. Fig. 4 is a view similar to Fig. 1 showing the opening of the first vane. Fig. 5 is a plan corresponding to the previous view. Fig. 6 shows the position of 45 the parts during the opening of the shutter; Fig. 7 shows the second vane open; Fig. 8 is a section of the apparatus taken on the line B—B of Fig. 5, showing the internal mechanism in the same position as Fig. 1. 50 Figs. 9 and 10 are two similar sections

showing two positions corresponding to Fig. 6. Fig. 11 corresponds to Fig. 7.

As can be seen on these drawings, the new device comprises a frame *a*, on which are mounted two vanes *b* and *c*, capable of turning on a pivot pin *d* and provided with springs which tend to open them in order to bring them into the positions shown in Figs. 4 and 7. These vanes are retained folded back against the frame when the apparatus is set, one by a tooth *e*² on a lever *e* (Fig. 1) which turns about *e*¹, and the other by a tooth *f*² on a second lever *f*, or auxiliary lever, mounted on the lever *e*. This second lever is capable of turning about the axis *e*¹ and can be held fast on the lever *e* by the aid of a milled head, lock-nut or button *f*¹. The end *f*³ of the lever *f* forms a pointer standing opposite a scale *e*³ divided into seconds on the lever *e*.

The tooth *e*² serves to retain the vane *b*, while the tooth *f*² serves to retain the vane *c*. When the lever *f* is moved relatively to the lever *e*, the angular distance apart of the two teeth *e*² and *f*² is varied. Consequently 80 the space of time which elapses between the opening of the two vanes is varied according to the desired duration of the exposure.

The lever *e* bears a pin *g*, and the lever *f* a pin *h* (Figs. 5 and 8), designed to effect 85 respectively the release of the mechanism operating the shutter in order to open and to close this shutter. By varying the relative positions of these two levers *e* and *f*, the angular distance apart of the two pins 90 is changed and consequently the time which elapses between the instant at which the first determines the opening of the shutter and the instant at which the second effects the closure thereof.

The lever *e* is provided with a detent *i* (Fig. 8) in engagement with a ratchet *i*¹ acted upon by a spring *i*² forming part of a clockwork-movement. This movement is wound up when the lever *e* is passed from 100 the position II (Fig. 7), to the position I (Fig. 1), which stresses the spring *i*².

A button *i*³ (Fig. 1) serves to determine the operation or the stoppage of the device. The button *i*³ carries an elastic blade *i*⁴, Fig. 105 8, which comes to bear against the balance *B* of the clockwork.

The mechanism acting on the presser-piece *j* of the shutter comprises a button *k* which, when the device is mounted on the 110

photographic apparatus, is opposite this presser-piece. This button is normally moved away from the presser-piece by a leaf spring k^1 , Fig. 8.

5 A cam l , Fig. 8, which has two projections l^1 and l^2 and is keyed on a shaft l^3 , is adapted to act on the end of the spring k^1 . In the interior of the cam is arranged a spiral spring l^4 (Fig. 8), which tends to turn it in the direction indicated by the arrow 1. The cam l is fixed to a disk m having two retaining notches m^1 and m^2 . In these notches there is adapted to engage the nose of a hook n , pivoted at n^1 and pressed against the disk by a spring n^2 .

10 The shaft l^3 extends through the front plate of the frame a and on its end is keyed a crank o , Fig. 1; to the latter is pivotally attached a slide p in which there can move 15 a button or pin q carried by the lever e .

15 The new arrangement is shown mounted on a verascope by the aid of a bayonet joint composed of a small base r (Fig. 1), having two holes r^1 and provided with a spring r^2 20 with a tooth r^3 , Fig. 3. On the other hand, there is provided on the verascope a plate s having two hooks s^1 .

25 In order to place the new device on the verascope, it is only necessary to bring the holes r^1 on to the hooks s^1 and then to move the device to the left; the noses of the hooks s^1 then come opposite the imperforate parts of the base r and the device is locked in position. The tooth r^3 falls behind the hook 30 s^1 , as shown in Fig. 3, which prevents any accidental separation of the device from the verascope; the device can only be removed by disengaging the tooth r^3 by hand and pushing it to the right.

35 40 The device being supposed placed on the verascope, the operation is as follows: The operator unfastens the milled head f^2 and turns the lever f relatively to the lever e in such a manner as to bring the pointer f^3 opposite the desired figure of the scale e^3 , according to the time the exposure is to last. He then tightens up the milled head in such a manner that the lever f forms part of the lever e and accompanies it in its rotary motion. He winds up the device, if it is not already wound up, by bringing the set of levers e and f to the position I, Fig. 1. In this position, the spring i^2 of the clockwork movement is stressed. The lever e , at the 45 end of its movement, acts by means of its button or pin q on the top of the slide p and turns the crank o , which brings it into the position shown in Fig. 1; the cam l takes up the position shown in Fig. 8; the spring of 50 this cam is likewise stressed; it is retained in the set position which has just been given it by the hook n of which the nose engages in the first notch m^1 of the disk m , Fig. 8. The operator moreover takes care to bring 55 the button t of the verascope to the time-ex-

posure position, and to set the shutter by turning the lever t^1 to the left. These operations can also be made before the apparatus is mounted on the verascope. All is thus prepared. The operator moves the button i^3 and brings it to the starting position. The clockwork movement sets itself in motion immediately. The operator then goes to the place which he is to occupy in order to be photographed. As the set of levers e and f turn in the direction x , Fig. 1, there arrives a moment at which the tooth e^2 leaves the vane b ; the latter under the action of its spring opens immediately, moving into the position shown in Fig. 4. The interior of 70 the vane b and the back of the vane c can be of a striking color, red for example. The appearance of these red surfaces indicates to the operator that the shutter is about to open. In fact an instant after the red signal has thus appeared, the pin g of the lever e which, in the rotary movement of this lever, has gradually approached a projection n^3 on the hook n (Fig. 8), raises this projection and disengages the nose of the hook 75 from the notch m^1 . The cam l is thus released and rapidly rotates through a fraction of a revolution. It is stopped by the engagement of the notch m^2 with the nose of the hook n . In this movement of rotation of the cam, the projection l^1 bears on the button k , depresses it as shown in Fig. 9, then passes the end of the leaf spring k^1 allowing this spring and the button k to rise, thus taking up the position shown in Fig. 10. 80 85 At the moment at which the button k has passed the position shown in Fig. 9, the presser-piece j of the shutter has been depressed sufficiently to determine the opening of the shutter. The shutter then remains 85 90 95 open during the desired time of the exposure. The closure of the shutter, when the time of exposure has elapsed, is effected by the pin h on the lever f ; this pin acts on a projection n^4 on the hook n (Fig. 11) and 100 105 disengages this hook from the notch m^2 . The cam l is again released and turns until the notch m^1 engages a fixed projection u , Fig. 11, which stops it. In this movement, the projection l^2 depresses the button k and 110 115 consequently the presser-piece j which closes the shutter. An instant after, the tooth f^2 releases the vane c which opens, Fig. 7; its reverse side and the surface c^1 form a signal indicating to the operator that the photograph is taken. If it be desired to take an instantaneous view, it is only necessary to bring the button t to the instantaneous position. The engagement of the cam l releases the shutter. In this case, the index f^3 is 120 125 brought into its extreme position. The appearance of the second signal follows very shortly after the taking of the photograph.

125 The above arrangements are only given by way of example, the forms, dimensions and 130

detail arrangements can be varied in all cases without altering the principle of the invention.

Claims:

- 5 1. In a device for automatically controlling the release of the shutters of photographic apparatus, annunciating vanes, a driving mechanism, levers actuated by said mechanism, means for adjusting the relative positions of the two levers and determining the duration of the exposure, means for allowing the levers to open the vanes, and means for allowing the levers to actuate the press-button of the shutter for opening and closing said shutter.
- 10 2. In a device for automatically controlling the release of the shutters of photographic apparatus, annunciating vanes, a driving mechanism, two levers actuated by said mechanism, projections on said levers, coöperating with the vanes, pins on said levers, a hook, a cam, retaining notches in said cam, in which the hook engages, and two projections on the cam, for acting upon the press-button of the shutter.
- 15 3. In a device for automatically controlling the release of the shutters of photographic apparatus, annunciating vanes, a driving mechanism, two levers actuated by said mechanism, projections on said levers, coöperating with the vanes, pins on said levers, a hook, a cam, and projections on said cam, adapted to act upon the press-button of the shutter.
- 20 4. In a device for automatically controlling the release of the shutters of photographic apparatus, annunciating vanes, a driving mechanism, levers actuated by said mechanism, means for winding up the driving mechanism by means of said levers, means for allowing the levers to open the vanes, and means for allowing the levers to actuate the press-button of the shutter for opening and closing said shutter.
- 25 5. In a device for automatically controlling the release of the shutters of photographic apparatus, annunciating vanes, a driving mechanism, levers actuated by said mechanism, means for adjusting the relative positions of the two levers and determining the duration of the exposure, means for allowing the levers to open the vanes, and means for allowing the levers to actuate the press-button of the shutter for opening and closing said shutter.
- 30 6. In a device for automatically controlling the release of the shutters of photographic apparatus, annunciating vanes, a driving mechanism, two levers actuated by said mechanism, projections on said levers, coöperating with the vanes, pins on said levers, a hook, a cam, retaining notches in said cam, in which the hook engages, and two projections on the cam, for acting upon the press-button of the shutter.
- 35 7. In a device for automatically controlling the release of the shutters of photographic apparatus, annunciating vanes, a driving mechanism, two variably angularly spaced apart levers, a projection on each lever for retaining the vanes, and a pin on each lever for opening or closing the shutter.

8. In a device for automatically controlling the release of the shutters of photographic apparatus, annunciating vanes, a driving mechanism, two variably angularly spaced apart levers, a projection on each lever for retaining the vanes, and a pin on each lever for opening or closing the shutter.

9. In a device for automatically controlling the release of the shutters of photographic apparatus, annunciating vanes, a driving mechanism, two variably angularly spaced apart levers, a projection on each lever for retaining the vanes, and a pin on each lever for opening or closing the shutter.

10. In a device for automatically controlling the release of the shutters of photographic apparatus, annunciating vanes, a driving mechanism, two variably angularly spaced apart levers, a projection on each lever for retaining the vanes, a pin on each lever, a hook, a spring cam, retaining notches on said cam, coöperating with the hooks, and projections on the cam, for acting upon the press-button of the shutter.

The foregoing specification of our improved automatic device for controlling the operation of photographic apparatus signed by us this 18th day of January, 1913.

LOUIS JOSEPH EMMANUEL COLARDEAU,
JULES RICHARD.
